Inventor:
George Bastian
By V. B. Singer, Atty.

UNITED STATES PATENT OFFICE.

GEORG BASTIAN, OF BERLIN-LICHTENBERG, GERMANY, ASSIGNOR TO G. GOLIASCH & CO., OF BERLIN-NEUKOLLN, GERMANY.

DICE-PLAYING APPARATUS.

Application filed February 10, 1928, Serial No. 253,406, and in Germany September 7, 1927.

My invention relates to improvements in a dice playing apparatus, and more particularly in apparatus in which the dice are disposed within a closed receptacle having a 5 transparent wall. The object of the improvements is to provide an apparatus of this class which is simple in construction, and with this object in view my invention consists in disposing the said receptacle 10 with the dice placed therein on an elastic support adapted to be thrown by elasticity in vertical or transverse direction. In the construction of the apparatus the receptacle is supported on a coiled spring mounted so 15 as to permit lateral oscillating movement or vertical reciprocating movement of the receptacle.

For the purpose of explaining the invention two examples embodying the same have 20 been shown in the accompanying drawings in which the same reference characters have been used in all the views to indicate corresponding parts. In said drawings,

Fig. 1, is an elevation showing the apparatus,

Fig. 2 is a top plan view of Fig. 1.

In the example shown in the drawings the apparatus consists of a base 1 made from wood or metal, a receptacle 4 of transparent material such as glass, celluloid, or the like, and a coiled spring 2 fixed to the base 1 and to the bottom of the receptacle 4. As

shown the receptacle 4 is in the form of a cap having a semi-spherical top and a bottom 3 in the form of a stopper of cork, rubber, or the like, pushed into the bottom part of the cap 4 and fixed to the top end of the spring 2. Preferably, the receptacle 4 consists of a preparation glass having a thick wall. Within the receptacle 4 there are the 40 dice 12.

For throwing the dice the receptacle 4 is pulled laterally by the hand of the player and released, whereby the dice are thrown outwardly and the top part of the apparatus is made to oscillate, until finally the 45 dice come to rest.

In the examples shown in the figures the caps 4 are formed with semi-spherical tops. But I wish it to be understood that I do not 50 limit myself to this feature, and that in some cases the top of the receptacle is flat or otherwise shaped.

I claim:

A dice playing apparatus, comprising a 55 receptacle of transparent material closed at its top and open at its bottom, a stopper for closing said receptacle at its bottom, and a flexible elastic member fixed to said stopper and supporting the receptacle.

In testimony whereof I hereunto affix my 60 signature.

GEORG BASTIAN.
